UNITED STATES PATENT OFFICE.

ELOF H. MEDÉN, OF ELIZABETH, NEW JERSEY, ASSIGNOR TO AMERICAN GASAC-CUMULATOR COMPANY, OF ELIZABETH, NEW JERSEY, A CORPORATION OF NEW JERSEY.

DUPLEX TRIGGER-CONTROL DEVICE.

Application filed April 5, 1920. Serial No. 371,176.

To all whom it may concern:

Be it known that I, ELOF H. MEDÉN, a subject of the King of Sweden, and a resident of Elizabeth, in the county of Union 5 and State of New Jersey, have invented an Improvement in Duplex Trigger-Control Devices, of which the following is a specification.

My invention relates to improvements by 10 the employment of which either a single one of a number of guns may be operated or all of which may be operated simultaneously as desired. In some cases, as for instance in aerial warfare, it is desirable that a plurality of independent guns shall be operated and fired simultaneously; also that it 15 shall be possible to operate and fire what I shall term herein the primary gun independently of the other guns which I shall 20 term herein the secondary guns.

It is the object of my invention to provide simple and efficient means extending from the primary to the secondary gun or guns whereby if desired the latter may be 25 operated simultaneously with the primary gun.

A further object of my invention is to provide such means with a device situated 30 in such proximity to the operating trigger or equivalent device of the primary gun that one of the fingers of the hand employed to operate a trigger of the primary gun may be used to actuate the said device to operate or fire the secondary gun or guns.

A still further object of my invention 35 is to provide means whereby in the employment of means for operating the secondary guns all lost motion between the said means and the trigger or equivalent device on the secondary gun or guns is eliminated and avoided.

Other objects and advantages of my invention will be pointed out in the detailed description thereof which follows or will 45 be apparent therefrom.

In order that my invention may be readily understood and its practical advantages appreciated, reference may be had to the accompanying drawings in which I have illustrated one embodiment thereof. However, 50 it is to be understood that my invention is susceptible of embodiment in other forms of construction than that shown.

In the drawings:

Fig. 1 is a horizontal sectional view of 55 a device embodying my invention, portions of the gun butts; that is, of the gun structure, being shown in plan;

Fig. 2 is a view in side elevation looking 60 toward the left in Fig. 1;

Fig. 3 is a view in side elevation looking 65 toward the right in Fig. 1;

Fig. 4 is a transverse sectional view taken 70 on the line 4—4 of Fig. 3, the top portion of the butt to which the trigger is connected being, for convenience of illustration, indicated in outline by dotted lines;

Fig. 5 is a transverse sectional view taken 75 on the line 5—5 of Fig. 2 the top portion of the butt to which the trigger is connected being, for convenience of illustration indicated in outline by dotted lines; and

Fig. 6 is a horizontal sectional view taken 80 on the line 6—6 of Fig. 2.

In the drawings I have illustrated my invention as employed in connection with two gun structures, only the butts thereof being shown, one of which structures, termed or described herein as the primary structure, being adapted to be operated and fired directly by the operator, while the other structure, termed or described herein as the secondary structure, is adapted to be operated by means constituting my invention. However, as already indicated, the said means 85 may be extended to and adapted for the operation of additional secondary gun structures as will be apparent.

In the drawings I have shown only the 90 butt portions of the gun structures, it being deemed unnecessary to show the barrel and other portions of such structure, as such portions constitute no part of my invention. It will be understood that my invention may be employed in connection with gun butts 95 of other forms or shapes and constructions than that shown.

Referring to the drawings: 1 designates a gun butt provided with a trigger guard 2 within which the trigger 3 is situated. This 100 trigger is operated in the usual way for effecting firing of the gun.

Referring now to the particular features 10 of the construction constituting an embodiment of my invention, 5 designates plates which are adapted to be secured upon the

opposite sides of the trigger guard 2. There are two of these plates associated with each gun and they are each provided with oblong openings 6 and with depressed portions 7. 5 Surrounding the sides and one end of the opening 6 of each plate an inturned flange 10 is provided. The opposite ends of this flange are continued by a shoulder-like portion 11 to which the depressed portion 7 is 10 connected. The flange 10 and the shoulder portion 11 constituting a continuation of the flanges of each of the plates 5 are adapted to project into the opening of the trigger guard as indicated in the drawings. The 15 lower portions of the plates 5 extend below the lower side of the trigger guard 2, as is clearly indicated in Figs. 2 and 3 of the drawings.

The plates 5 are attached and held in position upon the trigger guards 2 by spacer bolts 12, 13 and 14, one end of each of said bolts being riveted to one of said plates and the other end of each thereof being secured to the other plate by means of removable 25 headed screws 15. By removing these screws the plates 5 may be detached from the trigger guard.

The plates 5 are provided with openings 20 in alinement with each other.

30 In the drawings I have illustrated my invention as applied to and employed in connection with two gun structures. These structures are connected together by means of a shaft-like member which, for the sake 35 of lightness, preferably is hollow, as shown in Fig. 1. This shaft-like member consists of two parts, 21 and 22, the outer ends of which project into the openings 20 and are rotatably supported therein. The inner 0 ends of each of these parts 21 and 22 are serrated as indicated at 23. These serrations are adapted to interlock as indicated in Fig. 1 and to be held together in interlocking relation. For holding the inner 5 ends of the parts 21 and 22 in interlocked relation I have provided the externally 10 screw threaded sleeve-like part 24 which is permanently secured to the member 22 adjacent its inner end by means of a pin 25. 0 26 designates a collar secured to the other part 21 adjacent the end thereof by means 5 of a pin 27. The inner ends of the parts 21 and 22 are drawn together so as to effect 15 interlocking of the serrations or teeth 23 by means of a cap-like part 28 internally 20 screw threaded for engagement with the external screw threads upon the part 24. The closed end portion of the cap 28 is in engagement with the outer edge of the collar 26, as shown. By screwing the cap 28 toward the right in the usual way, the parts 21 and 22 constituting the shaft-like member extending between the gun structures are drawn together into interlocking 25 relationship as shown. By loosening the cap

part 28 it will be understood that these parts 21 and 22 may be adjusted rotatably with relation to each other. The purpose and object of this adjustment will be more fully set forth later on herein.

70 In order that the shaft-like member may be rotatably actuated, I have provided adjacent the outer end thereof a collar 30 situated directly below the lower side of the trigger guard 2, said collar being secured to the part 21 by means of a pin 31 which extends diametrically through the said collar and through the said part 21. Said pin is situated at the inner ends of slots 32, the outer ends of which open upon the outer end of the said part 21. The collar 30 is spaced from the opposing plates 5 by means of spacing collars 33 as clearly shown in Fig. 5 of the drawings. By providing the slots 32 and positioning the pin 31 therein as shown in Fig. 5 it is apparent that the collar 30 may be readily removed upon removal of the outer plate 5. The collar 30 is provided with a projection 35 which extends in a forward direction with respect to the gun structure, which projection is adapted to contact with a projection 36 situated intermediate the outer and inner ends of an auxiliary trigger 40 pivotally mounted upon the spacing connecting bolt 14. The auxiliary trigger 40 is retained with its projection 36 in contact with the under side of the projection 35 by reason of the engagement of a projection 41 on said trigger with the forward portion of the trigger guard 2, as shown in Fig. 2 of the drawings. The said projection 41 extends upwardly from the pivot of said auxiliary trigger and constitutes an extension thereof. The auxiliary trigger is protected by means of an auxiliary trigger guard 45 secured at one end to the spacing connecting bolt 13 and at its opposite end to the spacing connecting bolt 14. The portions of the latter end of the auxiliary guard 45 which are secured to the bolt 14 are situated upon opposite sides of the trigger 40 so as to retain the latter in central position upon the said bolt and hold it in proper and operative relation with respect to the projection 35 of the collar 30. 110 For convenience of description and identification I refer to the gun structure with which the projection 35, the auxiliary trigger 40 and the auxiliary trigger guard are associated as the "primary" gun structure. 115

120 The member 22 is provided near its outer end with a collar 50 which is situated inside of the inner of the plates 5 secured to the trigger guard 2 of the secondary gun structure. The said collar 50 is secured to the part 22 to rotate therewith by means of a pin 51 which extends through the said collar and through slots 52 in the part 22, the outer ends of which open upon the outer end of the said part. 125

53 designates an arm rigidly secured to the outer end of the collar 50 which arm projects outwardly and radially with respect to the said collar and the shaft connecting 5 the two gun structures. The outer end of said arm 53 is provided with a laterally and outwardly projecting portion 55 which should be situated in contact with the trigger 3 of the secondary gun structure, as is 10 shown in Fig. 3 of the drawings.

The purpose of the adjustable connection between the inner ends of the parts 21 and 22 of the shaft member is that the two parts 21 and 22 may be so adjusted as to cause 15 the projections 35 and 36 to be at all times in contact and also to cause the portion 55 to be at all times in contact with the trigger 3 of the secondary gun structure in order that when the auxiliary trigger 40 is pulled 20 there will be no lost motion between the said trigger 40 and the trigger 3 of the secondary gun structure. By the arrangement shown any movement of the auxiliary trigger 40 causes immediate movement of the 25 trigger or triggers 3 of the secondary gun structure or structures.

Although I have shown but two gun structures, the primary gun structure and the secondary gun structure, it will be understood that the device embodying my invention may be employed to operate an additional number of secondary gun structures, it being merely necessary to extend the part 22 or other corresponding part beyond 30 the first of the secondary gun structures and by providing between the first of such secondary gun structures and the second of said structures an adjustable construction such as is employed for connecting the inner 35 ends of the parts 21 and 22.

While as shown and as described the primary gun structure constitutes the outermost structure situated at one end or the other of a series of such structures, it will 45 be understood that the gun structure with which are associated the projection 35, the auxiliary trigger 40 and the auxiliary guard 45 and which I have termed herein the primary gun structure, may be situated between 50 the secondary gun structures so that the connections between the primary gun structure and the secondary structures will extend in opposite directions from the former.

In the operation of the device the operator 55 should with his forefinger press the trigger 3 of the primary gun structure and if he desires to operate the secondary gun structure he should simultaneously press the auxiliary trigger 40 with the middle finger. 60 By my invention I provide a device which is arranged for convenience in operation and which is positive and efficient in action.

The term "gun structure" employed herein is intended to designate any form of gun 65 with any form of gun stock or butt; also

the term or word "trigger" employed herein is intended to designate not only triggers like trigger 3 shown in the drawings but any form of trigger or other equivalent device for effecting the firing of a gun. 70

I claim:

1. In a duplex trigger control device, a plurality of gun structures each being provided with a trigger to effect firing thereof, the trigger of one of said structures adapted to be actuated independently of the trigger or triggers of the other structure or structures, and rotatable means connecting said structures, said means being provided with a device situated adjacent the trigger of the first named structure by which it is adapted to be actuated and said means having a device or devices situated adjacent the other gun structure or structures which is or are adapted to actuate only the triggers 80 of such structures to effect firing thereof. 85

2. A duplex trigger control mechanism comprising means extending between a primary and a secondary gun structure, a trigger for the primary gun structure by which alone the gun of said structure is adapted to be fired, a device situated adjacent the trigger of the said primary gun structure which device is adapted to be actuated independently of the trigger for the primary gun structure to effect actuation of the said means which extends between said structures, said means being provided with a device adjacent and associated with the secondary gun structure and being adapted to 90 contact with and actuate only the trigger thereof to effect firing of the same. 95

3. In a duplex trigger control device, the combination of primary and auxiliary gun structures each provided with a trigger to 100 effect firing of the guns of such structures, rotatable means extending between said structures, an auxiliary trigger situated adjacent the trigger of the primary gun structure, means whereby movement of said auxiliary trigger effects movement of the said means, and means whereby movement of the latter actuates only the triggers of said auxiliary gun structures to effect firing of 105 the guns thereof. 110

4. In a duplex trigger control device, the combination of primary and secondary gun structures each being provided with a trigger, the said primary structure being provided with an auxiliary trigger which is adapted 115 to operate only the trigger or triggers of the secondary gun structure or structures, a rotatable member extending between and supported upon the said gun structures, means intermediate the said auxiliary trigger and the said member whereby movement of said auxiliary trigger causes rotary movement of the said member and the said member being provided with a device or devices 120 which upon actuation of said member in 125 130

one direction only actuates the trigger or triggers of the secondary gun structure or structures to fire the same.

5. In a duplex trigger control device, the combination of a rotatable actuating member connecting and being in operative relation with respect to a plurality of guns each of which is provided with a trigger, an auxiliary trigger associated with one of said guns, the said auxiliary trigger and the trigger with which it is associated being independently operable and said auxiliary trigger operating the trigger or triggers of the other or others of said guns only, means intermediate said auxiliary trigger and the said actuating member whereby said member may be actuated by movement of said auxiliary trigger, and the said actuating member being provided with means whereby the trigger or triggers of the other gun structure or structures are operated upon actuation of said member.

6. In a duplex trigger control device, the combination of a plurality of guns each being provided with a trigger device for effecting firing thereof, an auxiliary trigger device associated with one of said guns, bearings supported upon the said guns, a rotatable shaft supported in said bearings and extending between said guns, said shaft consisting of a plurality of parts rotatably adjustable with relation to each other, means intermediate said auxiliary trigger device and the said rotatable shaft for rotating the latter and a tripping device or devices carried by the said rotatable shaft, which device or devices is or are adapted to trip the trigger or triggers of the other gun or guns.

7. In a duplex trigger control device, the combination of a plurality of gun structures, one of which being the primary and the other or others being the secondary structures, each of said structures being provided with devices for effecting firing thereof, bearing members detachably secured to and supported upon such structures, a rotatable shaft supported in said bearings and extending between said structures, said shaft comprising a plurality of parts, which parts are adapted to be rotatably adjusted with respect to each other, means for connecting the said parts together in such adjusted positions, an auxiliary trigger associated with the primary structure, means intermediate said auxiliary trigger and said rotatable shaft whereby actuation of said auxiliary trigger effects partial rotation of said rotatable shaft, and means carried by said rotatable shaft for actuating the devices for effecting firing of the said secondary gun structure or structures.

8. In a duplex trigger control device, the combination of a plurality of guns each being provided with a trigger and a trigger guard, plates situated upon opposite sides

of each of said guards and secured thereto, said plates being provided with aligned openings extending therethrough constituting bearings, an auxiliary trigger device pivotally supported upon the plates of one of said guns, a rotatable shaft-like member supported in the bearings upon said plates and extending between the said guns, means intermediate the auxiliary trigger device and the said shaft-like member whereby upon actuation of said auxiliary trigger device said shaft-like member is partially rotated, and means carried by said shaft-like member which is adapted to contact with the trigger or triggers of the other of said gun or guns for actuating the same to effect firing thereof simultaneously with the firing of the gun with which the said auxiliary trigger is associated.

9. In combination primary and secondary guns, the said primary gun having two triggers associated therewith, one of which is adapted to effect firing of the said primary gun and the other of which is adapted to effect firing of the said secondary gun or guns only, and rotatable means intermediate the latter trigger and the said secondary gun or guns whereby upon actuation of the said latter trigger firing of the said secondary gun or guns is effected.

10. In a duplex trigger control device, the combination of primary and secondary guns, the said primary gun being provided with two triggers adapted to be simultaneously actuated, one of said triggers being adapted to effect firing of said primary gun only, the other of said triggers being adapted to effect firing of the secondary gun or guns only, a rotatable member supported upon the primary and secondary guns and extending between the same, said rotatable member being adapted to be actuated by the last mentioned trigger, and means intermediate the said rotatable member and the said secondary gun or guns whereby actuation of said member effects firing of said secondary gun or guns.

11. In a duplex trigger control device, the combination of primary and secondary guns, the said primary gun being provided with a trigger to effect the firing thereof and an auxiliary trigger, and the said secondary guns being likewise provided with triggers for effecting firing thereof, a rotatable member supported upon the primary and secondary guns and extending between the same, said member comprising a plurality of parts rotatably adjustable with respect to each other and means for securing the said parts together in adjusted position, means intermediate the said auxiliary trigger and the said rotatable member whereby upon actuation of the latter the said rotatable device is partially rotated, and means normally in contact with the trig-

gers of the secondary guns which means is adapted to be actuated upon actuation of the said rotatable member to actuate said triggers, and the said primary and auxiliary triggers associated with the primary gun being adapted to be actuated simultaneously whereby simultaneous firing of the primary and secondary guns is effected.

12. A duplex trigger control device comprising a rotatable control member, bearing means supported upon the trigger guard of a gun structure for supporting a portion of said rotatable control member, an auxiliary trigger supported upon said bearing means and situated outside of the said guard, means intermediate the said auxiliary trigger and said control member whereby actuation of said auxiliary trigger effects movement of said control member, and an auxiliary trigger guard for guarding and protecting said auxiliary trigger, said auxiliary guard being supported upon the said bearing means.

13. A duplex trigger control device comprising a shaft-like member consisting of a plurality of parts rotatably adjustable with respect to each other and means for securing the said parts together in adjusted position.

14. A duplex trigger control device comprising a shaft-like member, consisting of a plurality of parts rotatably adjustable with respect to each other, means for securing the said parts together in adjusted position, and means associated with said shaft-like member whereby a plurality of guns may be fired simultaneously.

15. In a duplex trigger control device, the combination of primary and secondary guns, a shaft-like member supported upon said guns said member comprising a plurality of parts rotatably adjustable with respect to each other, means for securing said parts together in adjusted position, means for firing said primary gun and means associated with said shaft-like member whereby all of and only said auxiliary guns may be fired simultaneously with each other independently of the said primary gun, the latter being adapted to be fired by the means provided therefor.

16. A mechanism of the character described, comprising in combination a plurality of gun structures, gun firing means associated with each structure, said gun firing means adapted to be actuated independently of each other, an auxiliary trigger device associated with one of the said gun structures and being situated in proximity to the gun firing means thereof and being adapted to operate only the firing means of the other gun structures, and a rigid rotatable means intermediate the said auxiliary control device and the gun firing means of the other gun or guns whereby the gun firing means

of the said other gun or guns may be actuated either simultaneously with or independently of the gun firing means of the first named gun.

17. A mechanism of the character described, comprising in combination primary and secondary gun structures each being provided with means for effecting the firing of the guns of each of said structures, a device associated with the said primary gun structure and being situated in proximity to the firing means thereof whereby with one finger an operator may actuate the said means and with another finger actuate the said device which operates only to fire the guns of the secondary gun structure or structures, a rotatable shaft-like member extending between the said primary and secondary gun structures, said member being provided with means adapted to actuate the firing means only of the said secondary gun structures, and means intermediate the said device and the said member whereby actuation of said device causes movement of said member to thereby effect actuation only of the firing means of the secondary gun structure or structures.

18. In duplex trigger control mechanism, the combination of primary and secondary gun structures, a trigger associated with each structure for tripping the gun firing mechanism thereof, an auxiliary trigger associated with the primary gun structure and situated in proximity to the trigger thereof whereby the said triggers may be actuated either independently of each other or simultaneously, the said auxiliary trigger operating only to operate the triggers of the secondary gun structures, a rotatable shaft-like member extending between the said gun structures, said member being provided with devices for actuating the trigger or triggers of the said secondary gun or gun structures, and means intermediate the said auxiliary trigger and the said rotatable member whereby movement of the said auxiliary trigger effects movement of said movable member to actuate only the triggers of the secondary gun structures substantially as described.

19. In a duplex trigger control mechanism, the combination of primary and secondary guns each provided with a trigger and a trigger guard, the said primary gun being provided with an auxiliary trigger having connection with its trigger guard, and rigid rotatable means extending between said guns and mounted upon said trigger or trigger guards for actuating the triggers of the said secondary gun or guns only and the said auxiliary trigger operating only to actuate said means.

20. In a duplex trigger control mechanism, the combination of a plurality of guns each provided with a trigger and a trigger

guard, an auxiliary trigger mounted upon the guard of one of said guns in adjacent relation to the trigger thereof, and rotatable shaft-like means intermediate the said auxiliary trigger and the trigger of the other gun whereby upon actuation of the said auxiliary trigger the said last named trigger

only is actuated to effect firing of the said other gun.

In testimony that I claim the foregoing 10 as my invention I have hereunto signed my name this 1 day of April A. D., 1920.

ELOF H. MEDÉN.
